Russell W. Everett,
ATTORNEY.

UNITED STATES PATENT OFFICE

CHARLES L. PARKER, OF NEWARK, NEW JERSEY.

SAFETY-CATCH FOR PINS, BROOCHES, AND THE LIKE.

1,313,010.

Specification of Letters Patent.

Patented Aug. 12, 1919.

Application filed November 10, 1915. Serial No. 60,631.

To all whom it may concern:

Be it known that I, CHARLES L. PARKER, a citizen of the United States, and a resident of Newark, in the county of Essex and 5 State of New Jersey, have invented certain new and useful Improvements in Safety-Catches for Pins, Brooches, and the like, of which the following is a specification.

This invention relates to that class of 10 safety catches in which a catch is pivoted at the base of the hooked keeper with one arm lying inside the keeper adapted to close the same and the other arm projecting at the closed side of the keeper, a 15 spring normally holding said catch in closed position.

The objects of the invention are to provide a spring which engages the arm inside the keeper to close the same; to employ a 20 substantially V-shaped catch; to secure compactness and a neat and inconspicuous appearance; to locate the spring as well as one 25 arm of the catch inside the keeper; to secure simplicity of construction and operation, and to obtain other advantages and 30 results as may be brought out in the following description.

Referring to the accompanying drawings, 35 in which like numerals of reference indicate the same parts throughout the several views,

Figure 1 is an underneath or back view of 40 a pin or brooch to which my safety catch has been applied;

Fig. 2 is an edge view of the same at right 45 angles to the pin shaft;

Fig. 3 is an edge view transverse to the 50 pin shaft locking at the open side of the keeper and from the side thereof toward which the shaft opens;

Figs. 4 and 5 are sections on the line A—A 55 Fig. 1 showing the safety catch in closed and opened position respectively;

Fig. 6 is a perspective view of the keeper 60 partly in section, and

Fig. 7 is a perspective view of the keeper 65 before its feet are turned into parallel planes.

In the specific embodiment of the invention 70 shown in said drawings, 1 indicates a body portion of a pin, brooch or similar article of any kind having a pin shaft 2 pivotally connected at one end to the body portion as at 3 and adapted at its pointed end to engage beneath a keeper 4. My im- 75 proved safety catch is applied to this keeper 4 for the purpose of retaining the pin shaft

against inadvertent escape as will be understood.

The keeper 4 is apertured near its base or attachment to the body portion 1, in a plane 60 transverse to that in which the pin shaft 2 swings, and in this aperture is pivoted a somewhat V-shaped catch 5 with its arms extending upward and projecting one at the open side of the keeper and the other at the 65 closed side, as clearly shown in the drawings. When the catch is rocked on its pivot to cause the arm 6 to lie against the back or closed side of the keeper, the other arm 7 extends to or toward the extremity of the 70 hook portion of the keeper so as to close the opening of the keeper against escape of the pin shaft, as shown in Figs. 3 and 4. On the other hand when the arm 6 is swung away from the back or closed side of the 75 keeper as shown in Fig. 5 the other arm 7 swings inwardly beneath the hooked portion of the keeper past the pin shaft 2 so that said pin shaft may be freely released from the keeper. 80

The particular purpose of my invention is to provide spring means directly engaging the arm 7 to hold the catch 5 normally in closed position as shown in Figs. 3 and 4, and to this end I stamp out of the keeper 85 itself a spring 8, leaving the same integrally attached at the point of the hook portion of the keeper but free from the keeper at its opposite end and for its entire length. Preferably this spring 8 is stamped out as clearly 90 shown in Figs. 6 and 7, and comprises a median strip of the keeper as shown in Fig. 7. Stamping it out thus provides the aperture in the keeper above referred to to receive the V-shaped catch, and afterward the 95 feet 9, 9 of the keeper, which is of a single thickness of sheet metal are twisted a quarter turn as shown in the drawings. The end of the spring 8 is then cut off sufficiently to allow it to lie between the arms of the 100 V-shaped catch, as shown and said spring is given a "set" or normal position which will cause it to press at its extremity against the arm 6 of the V-shaped catch and thus swing said catch into closed position. At 105 the same time, the catch can obviously be swung open against the power of the spring 8 by means of the other arm or finger piece 5.

By the construction thus described, a 110 safety catch is provided which is not only simple and easy to make, but which is very

durable and effective. Furthermore, the spring 8 does not project so as to cause any obstruction, nor is it conspicuous in any way so as to detract from appearances. In 5 fact the said spring occupies space which would otherwise be used for nothing, and is hardly noticeable. At the same time it effectively holds the catch always in closed position unless it is positively opened by 10 the user. Instead of the spring being integral with the keeper, it of course could be mounted thereon in any suitable manner to accomplish the results set forth herein.

Obviously, many modifications and 15 changes may be made in manufacturing my improved safety catch without departing from the spirit and scope of the invention, and I do not wish to be understood as restricting myself except as required by the 20 following claims when construed in the light of the prior art.

Having thus described the invention, what I claim is:

1. In a device of the character described, 25 the combination with a hooked keeper, of a pivoted catch having an arm lying inside said keeper and adapted to close the same and another arm projecting at the closed side of the keeper, and a spring engaging 30 the said arm inside the keeper to normally hold it in closed position.

2. In a device of the character described, the combination with a hooked keeper, of a pivoted catch having an arm lying inside 35 said keeper and adapted to close the same and another arm projecting at the closed side of the keeper, and a spring between said arms of the catch engaging the said arm inside the keeper to normally hold it 40 in closed position.

3. In a device of the character described, the combination with a hooked keeper, of a pivoted catch having an arm lying inside 45 said keeper and adapted to close the same and another arm projecting at the closed side of the keeper, and a spring projecting from the hooked portion of the keeper into engagement with the said arm inside the keeper to normally hold it in closed position.

4. In a device of the character described, 50 the combination with a hooked keeper, of a substantially V-shaped catch pivoted at the base of the keeper with one arm lying inside said keeper and adapted to close the same 55 and another arm projecting at the closed side of the keeper, and a spring engaging the said arm inside the keeper to normally hold it in closed position.

5. In a device of the character described, 60 the combination with a hooked keeper, of a substantially V-shaped catch pivoted at the base of the keeper with one arm lying inside said keeper and adapted to close the

same and another arm projecting at the closed side of the keeper, and a spring between 65 said arms of the catch engaging the said arm inside the keeper to normally hold it in closed position.

6. In a device of the character described, the combination with a hooked keeper, of a 70 substantially V-shaped catch pivoted at the base of the keeper with one arm lying inside said keeper and adapted to close the same and another arm projecting at the closed side of the keeper, and a spring projecting 75 from the hooked portion of the keeper into engagement with the said arm inside the keeper to normally hold it in closed position.

7. In a device of the character described, 80 the combination with a hooked keeper, of a pivoted catch having an arm inside the keeper adapted to close the same, and a spring projecting from the hooked portion 85 of the keeper into engagement with said arm to normally hold it in closed position.

8. In a device of the character described, the combination of a hooked keeper having a leaf spring stamped longitudinally out of 90 its hook portion with its free end away from the free end of the hook, and a catch pivoted to said keeper and normally held in closed position by said spring.

9. In a device of the character described, the combination of a hooked keeper having 95 a spring stamped out of the longitudinal middle portion of its hook part with its free end away from the hook and its other end near the point of the hook, and a catch pivoted in the aperture formed by stamping out said spring and normally held in 100 closed position by said spring.

10. In a device of the character described, the combination of a keeper having a spring stamped out of the longitudinal middle portion of its hook part with its free end away from the hook and forming a slot opening 105 through the opposite end of the keeper, and a V-shaped catch pivoted in said slot and normally held in closed position by said 110 spring.

11. In a device of the character described, the combination of a hooked keeper formed out of sheet metal and having a spring stamped out of the longitudinal middle portion of its hook part with its free end away 115 from the hook and forming a slot opening through the opposite end of the keeper, the portions of the keeper on opposite sides of the open end of said slot being twisted substantially a quarter turn to form parallel feet, and a catch pivoted in said slot and normally held in closed position by said 120 spring.

CHAS. L. PARKER.
